DESIGN FOR A SHOE

Kenneth B. Keyes, New York, N. Y., assignor to Swan Shoe Company, Inc., Baltimore, Md., a corporation of Maryland

Application December 7, 1940, Serial No. 97,149

Term of patent 3½ years

To all whom it may concern:

Be it known that I, Kenneth B. Keyes, a citizen of the United States, residing at New York, in the county of New York and State of New York, have invented a new, original, and ornamental Design for a Shoe, of which the following is a specification, reference being had to the accompanying drawing, forming part thereof.

Fig. 1 is a view in side elevation of a shoe showing my new design.

Fig. 2 is a view in top plan of the shoe.

Fig. 3 is a view in front elevation of the shoe.

My design for a shoe is characterized by the configuration of the sole formation, comprising a flat thin outer sole; a wedge-heel insert; a platform portion with rounded edges and a beaded welt inset from the platform portion and of a color contrasting to that of the color of the platform portion.

I claim:

The ornamental design for a shoe, as shown and described.

KENNETH B. KEYES.
